UNITED STATES PATENT OFFICE.

WALTER S. GERTS, OF RIVER FOREST, ILLINOIS.

DESIGN FOR A FOUNTAIN PEN.

60,283.

Specification for Design.

Patented Jan. 17, 1922.

Application filed February 4, 1921. Serial No. 442,554. Term of patent 3½ years.

To all whom it may concern:

Be it known that I, WALTER S. GERTS, a citizen of the United States, residing at River Forest, in the county of Cook and State of Illinois, have invented a new, original, and ornamental Design for a Fountain Pen, of which the following is a specification, reference being had to the accompanying drawing, forming a part thereof.

On the drawing, the figure is a side elevational view showing my new design.

The important feature of my new design is the irregular roughened outer surface which is highly ornamental besides affording a good grip.

I claim:

The ornamental design for a fountain pen as shown.

In witness whereof, I hereunto subscribe my name this 1st day of February, A. D., 1921.

WALTER S. GERTS.
